(57) **CLAIM**

The ornamental design for a coordinate input device, as shown and described.

DESCRIPTION

FIG. 1 is a left-rear-bottom perspective view of a coordinate input device according to our new design, wherein legs of the device are in a first position;

FIG. 2 is a front elevational view thereof;

FIG. 3 is a rear elevational view thereof;

FIG. 4 is a left side elevational view thereof, wherein the right side elevational view is a mirror image of the left side elevational view;

FIG. 5 is a top plan view thereof;

FIG. 6 is a bottom plan view thereof;

FIG. 7 is a left-rear-bottom perspective view thereof, wherein legs of the device are in a second position;

FIG. 8 is a front elevational view thereof;

FIG. 9 is a rear elevational view thereof;

FIG. 10 is a left side elevational view thereof, wherein the right side elevational view is a mirror image of the left side elevational view; and,

FIG. 11 is a bottom plan view thereof.

The broken lines show portions of the coordinate input device which form no part of the claimed design.
